UNITED STATES PATENT OFFICE.

PAUL F. KENNEDY, OF MARION, OHIO.

MAGNETIC PEEL.

Application filed September 26, 1923. Serial No. 665,030.

To all whom it may concern:

Be it known that I, PAUL F. KENNEDY, a citizen of the United States, residing at Marion, in the county of Marion and State 5 of Ohio, have invented new and useful Improvements in Magnetic Peels, of which the following is a specification.

This invention relates to hoisting devices, particularly those of the magnetic type, 10 and has for its object the provision of a magnetic peel designed to be used in connection with a regulation charging machine used to charge raw material into an open hearth furnace. It is well known that the ordinary method of charging such furnaces 15 is to use a small charging car which is filled with miscellaneous pieces of scrap. Another method is for the workman to place large pieces of scrap on a flat peel by hand. These old methods are awkward and are slow, tedious and unsatisfactory.

With the above facts in view I have designed the present device which eliminates all this unnecessary work and accomplishes 25 the same result in a very short time. Ordinarily charging machines are electrically operated and as a consequence power is handy for the energization of the magnet used in connection with my device.

30 An important object is the provision of a magnetic peel which will be simple and inexpensive in manufacture, highly efficient in use, positive in action, efficient and durable in service and a general improvement in the art.

With the above and other objects and advantages in view the invention consists in the details of construction to be herein-after more fully described and claimed and 40 illustrated in the accompanying drawings, in which:

Figure 1 is a side elevation of the device showing it mounted upon a portion of a charging machine;

45 Figure 2 is a plan view and

Figures 3 and 4 are detail views showing the connection of the head with the charging machine.

50 In carrying out my invention I provide a main body 10 which may be formed preferably as a single casting and which includes an elongated arm 11 and a depending shank 12 which is relatively wide and which has its side edges formed with retaining flanges 13. This shank is also 55 formed with a hole 14.

Mounted upon the free end of the arm portion 11 is an electromagnet 15 of suitable size and shape and having any necessary winding depending upon the strength of 60 the current to be used and to a certain extent upon the probable weight of the scraps to be handled. This magnet is shown as held in position by having its core 16 provided with a reduced extension 17 passing through the arm 11 and carrying a nut 18. The feed cables for supplying current to the magnet are indicated by the numerals 19 and 20 and are housed within a conduit 21 mounted upon one side of the arm 11 70 and held by brackets or clips 22.

A portion of the charging machine is indicated by the letter A and as is well known this arm or head of the charging machine carries a plate B through which 75 projects a retractable plunger C.

In mounting my peel, the socket portion or shank 12 is engaged upon the plate B while the plunger C is retracted. When the parts are in such position that the hole 80 14 in the shank or socket registers with the plunger C, the plunger is extended so as to enter this hole which results in locking the peel firmly upon the charging machine.

It is of course obvious that when current 85 is supplied to the magnet by closing the circuit through any suitable switch not shown, the magnet will attract and pick up iron scraps of any kind so that they may be readily dropped into the furnace when the 90 switch is opened to break the circuit. The device is very simple and inexpensive and easy to operate so that it should recommend itself to those having occasion to employ its services. As the parts are so few it is 95 apparent that there is nothing to get out of order so that the device should have a long life and satisfactorily perform all of its functions.

While I have shown and described the 100 preferred embodiment of my invention it is of course to be understood that I reserve the right to make such changes in the form, construction and arrangement of parts as will not depart from the spirit of the invention or the scope of the subjoined claims.

Having thus described my invention I claim:

1. In combination with a charging machine, a magnetic peel comprising an elongated arm carrying an electromagnet, the 110 charging machine having a plate and a

plunger projectable therethrough, said arm terminating at one end in a vertical socket engaging upon said plate and formed with a hole receiving said plunger.

5 2. In combination with a charging machine, a magnetic peel comprising an elongated arm, an electromagnet mounted upon one end thereof, a depending shank on the other end of said arm formed with retain-

ing flanges and formed with a hole, the 10 charging machine carrying a plate having a plunger projectable therethrough, said plate being received between the flanges on said shank and said hole receiving said plunger.

15 In testimony whereof I affix my signature.

PAUL F. KENNEDY.
